UNITED STATES PATENT OFFICE.

LEWIS A. ASPINWALL, OF ALBANY, NEW YORK.

POTATO-DIGGER.

SPECIFICATION forming part of Letters Patent No. 224,123, dated February 3, 1880.

Application filed September 23, 1879. Patented in England, November 5, 1878.

To all whom it may concern:

Be it known that I, LEWIS AUGUSTUS ASPINWALL, of Albany, in the State of New York, United States of America, but at present of 33 Chancery Lane, in the county of Middlesex, London, England, have invented new and useful Improvements in the Construction of Potato-Diggers, which improvements are fully set forth in the following specification, reference being had to the accompanying drawings.

In the specification of a previous United States patent, dated 24th April, 1877, No. 189,911, I have described a separator consisting of two blades or paddles converging at the outside end and held at the other end by a ring.

Now, according to this present invention, I construct a separator consisting, mainly, of two bars or two pairs of bars, by preference flat, of a peculiar construction. Each of these bars is of a step-by-step construction, and arranged so as to form a kind of screw that is not of a continuous line, as an ordinary screw, but of sections or steps. I prefer to taper and split the outer ends and to terminate them in curves instead of steps. The steps may be angular or rounded. These screw-bars are fastened to a head, disk, or ring on a barrel or boss 30 revolving on a fixed stud or on a spindle supported in the side frame of the machine.

The rotary motion may be imparted in a similar way as described in the aforesaid previous patent specification.

I prefer to make the bars of such a size or section as to vibrate slightly by the movement and working of the implement, in order to prevent the accumulation of and clogging with earth.

The number of bars may be varied according to size and requirements of the machine.

I prefer not to use any cross-bars or connections between the aforesaid step screw-bars.

My improvements will be fully understood by reference to the accompanying drawings, of which—

Figure 1 is a side elevation of the machine or implement; Fig. 2, a vertical longitudinal section through same, and Fig. 3 a plan. Figs. 50 4 to 10 are details.

The platform A' is carried and connected

with the barrel of the top frame, A, by the two straps A², in which is the wheel-axle B, which carries the two loose carriage-wheels C and C'. A is the top frame of the machine. It has several bolt-holes, a. The platform A' and the top frame, A, are united by a bolt, a', which may be placed in any one of the holes a, whereby the position of the pole P, which is united to the platform A', can be adjusted laterally. 55

To the top frame, A, is fastened a bracket, r, which is securely stayed by means of the stay or strap r', and, in combination with the lever G, serves to raise the plow D from off the ground when the implement is to be turned 60 or conveyed along without working, for as the lever G is pulled back the roller r² rides on the platform A' and the lever r³ is brought into a vertical position, thereby raising the bracket r, and with it the top frame, A, to which it is 65 connected, and to which the plow D is also connected by the arm D'.

The screw F, passing through the nut f on the frame A and abutting against the lead-wheel frame N, which at its upper or back extensions, N' and N², is jointed to the frame A, serves to regulate the depth to which the plow D enters the ground, the front or lead wheel, O', running in the furrow and carrying the colter N³. 70

The separator is shown in one form at Figs. 4 and 5, the former being a side view and the latter an end view of same. It is fixed on a spindle, d, which works in a long boss on the bracket or plate g, which, by means of three 75 bolts, is secured to the side frame, A³, of the machine. 80

e and e' are two pairs of bars, by preference flat, or they may be of an oval or other section. The outer bars, e, start from opposite sides of a 85 boss, ring, or disk, e, and proceed step by step in a mainly circular or curved direction, and so as to form a kind of screw, but not of a continuous line, as an ordinary screw, but of sections or steps. The bars e' are, by preference, 90 tapered off toward the outer ends, as shown. The outer bars, e, are, by preference, split at the ends, as shown. It will be noticed that the step-by-step form in this case only extends part of their length, and I prefer to 95 terminate their outer or free ends in easy curves, as here shown. 100

The spindle *d*, supported in and free to revolve in the boss *g*, as described, is on the outer end fitted with a pinion, *M*, which receives rotary motion from the tooth-wheel *L*, 5 fixed on the axle *B*, when the road-wheel *C'*, which is loose on the same axle, is clutched in with it and when the machine is traveled along over the ground. The road-wheel *C'* is clutched in with the tooth-wheel *L* by throwing the pawl *J* into the ratchet-wheel *K*, which is fast 10 on the axle *B*. The pawl *J* is jointed to the plate *J'*, which is bolted to the nave of the traveling wheel *C'*.

j is a bent spring for holding the pawl in 15 gear, or for holding it quite out of gear when raised into the position shown in dotted lines.

The separator might be made to revolve on a fixed stud, instead of being fixed on a spindle, as here shown.

20 Fig. 6 is a view of a separator with two of the bars *c c'* removed, so as to show more clearly how the bars *c c'* are arranged. Fig. 7 is a side view, and Fig. 8 an end view, of a separator with two step screw-bars *c* only.

25 The ends of the bars *c c'* serve to separate the potatoes from their tops.

The number of bars may be varied according to size and requirements of the machine.

I prefer not to use any cross-bars or connection between the aforesaid step screw-bars. 30 The step parts of the bars may be made with slightly-rounded corners; but I prefer to make them sharp, as shown.

The plowshare *D*, which is shown separately in side elevation and plan, Figs. 9 and 10, has 35 at the back a round bar, upon which are several short fingers, *q*. Five of these are shown. They have stops that prevent them falling; but they are free to swing upwardly upon the round bar. These fingers are to prevent the 40 separator being stopped or broken in case of a stone lodging in the revolving separator, as the fingers will lift; but they will not drop down lower than the position shown.

I claim as my invention—

1. In a potato-digging machine, a revolving separator composed of a head, *e*, and two or more bars, *c c'*, connected thereto, said bars being of an approximately helical form, with offsets or steps, substantially as and for the 50 purposes set forth.

2. The combination, in a potato-digger, of the plow *D* and short fingers *q* and their stop-hinge, with a separator that is formed of a head, *e*, and two or more bars, *c c'*, connected 55 thereto and provided with off-sets or steps, substantially as and for the purposes set forth.

L. AUGS. ASPINWALL.
